CLAIM

The ornamental design for a hockey stick, as shown and described.

DESCRIPTION

FIG. 1 is a front, left perspective view of a hockey stick showing my new design;
FIG. 2 is a left side view thereof;
FIG. 3 is a right side view thereof;
FIG. 4 is a front view thereof;
FIG. 5 is a rear view thereof;
FIG. 6 is a bottom view thereof;
FIG. 7 is a top view thereof; and,
FIG. 8 is a cross-sectional view at 8-8 in FIG. 2 thereof.
The contrast in shading represents a contrast in appearance only and does not represent any particular color, material, texture or finish. The uneven-length broken lines immediately adjacent to the shaded area represent unclaimed boundaries of the design. The even-length broken lines showing the remainder of the hockey stick represent unclaimed subject matter and form no part of the claimed design.
